TUBULAR VAPOR GENERATING AND VAPOR SUPERHEATING UNITS

Willem F. C. Schaap, London, England, assignor to The Babcock & Wilcox Company, New York, N. Y., a corporation of New Jersey

Application December 18, 1953, Serial No. 399,115

6 Claims. (Cl. 122—392)

This invention relates to tubular vapor generating and vapor heating units of the kind comprising a furnace chamber with vapor generating wall tubes and with an outlet for the passage of gases from an upper region of the chamber to a lateral gas pass followed by a downpass, the lateral gas pass containing upright vapor heating tubes and the downpass containing vapor heating tubes extending across the pass. In a unit of this kind deposits falling from the upright tubes may be collected by a hopper or hoppers for discharge to the furnace chamber, so that disposal of deposits dislodged from the tubes is facilitated. In the downpass, however, deposits removed from an upper row of tubes or from an upper tube bank may find lodgement on a lower row of tubes or on the tubes of a lower tube bank within the pass. Such difficulty is aggravated if, as may be the case, the horizontal tube pitch in a lower tube bank is less than that in an upper tube bank. It is a matter of importance, therefore, to void if possible under all conditions of operation the formation on tubes in the downpass of deposits which when removed form lumps of appreciable size and to this end the deposit forming material contained in the furnace gases should be adequately cooled before reaching the downpass. The difficulty of obtaining adequate cooling is accentuated in vapor generating and vapor heating units for providing high pressure and high temperature vapor, since the extent of the vapor heating surfaces in such units tends to become excessive unless a relatively high gas temperature at the inlet to the vapor heating surface prevails. An object of the invention is the provision of an improved form of unit for the production of vapor at high temperature and pressure and having an arrangement of vapor heating surfaces economical to install and favorable to the maintenance of the vapor heating surfaces in good condition for effecting heat exchange.

In a tubular vapor generating and vapor heating unit of the kind specified the lateral pass extends above and contains vapor heating tubes disposed above the downpass, whilst means are provided for effecting interception of at least the larger pieces of solid matter which fall in the lateral pass towards the downpass.

The invention will now be described, by way of example, with reference to the accompanying partly diagrammatic drawings, in which:

Figure 1 is a sectional side elevation through a steam generating and superheating unit, taken on the line I—I of Figure 3 and as viewed in the direction indicated by the arrows;

Figure 2 is a sectional side elevation of part only of the unit shown in Figure 1, taken on the line II—II of Figure 3;

Figure 3 is a sectional plan view taken on the line III—III of Figure 1;

Figure 4 is a sectional plan view taken on the line IV—IV of Figure 1;

Figure 5 is a fragmentary sectional plan view of a gas

2

pass boundary, as shown in Figure 4, but drawn to a larger scale;

Figure 6 is a sectional plan view taken on the line VI—VI of Figure 1;

Figure 7 is a sectional plan view taken on the line VII—VII of Figure 1;

Figure 8 is a sectional front elevation taken on the line VIII—VIII of Figure 7; and

Figures 9 and 10 are sectional side elevations of a modified construction and correspond to the upper right hand parts of Figures 1 and 2 respectively.

A vertically elongated furnace chamber 1 of rectangular cross-section is formed with a hopper bottom 2 and has its front wall 3, rear wall 4 and side walls 5 and 6 lined with contiguous or closely spaced, steam generating, wall cooling tubes. Thus tubes 10 connected at their lower ends to an inlet header 11 line the front wall of the hopper bottom 2, and thence extend vertically upwards to approximately the mid-height of the furnace chamber, where they are bent inwardly to form an arch 12, above which they return to the plane of the lower part of the front wall and continue vertically upwards to the roof 13 of the furnace chamber, through which they extend, the tubes being connected at their upper ends to a steam and water drum 14. Tubes 17 connected at their lower ends to an inlet header 18 line the rear wall of the hopper bottom 2 and thence extend vertically upwards to a level above that of the arch 12, and below that of a lateral gas outlet 19 from the furnace chamber, at which level alternate tubes, designated by 17a, are bent forwardly towards the wall 3 to form an arch 20 which extends across the full width of the furnace chamber and which extends approximately a quarter of the depth of the furnace towards the front wall. The remainder of the tubes 17, designated by 17b, extend vertically upwards as far as the roof 13, at which they are bent forwardly of the furnace chamber and extend towards and through the front wall 3, serving to line the roof 13, and are connected at their upper ends to the steam and water drum 14. Above the arch 20, alternate tubes designated 17aa of the tubes 17a extend vertically upward to the roof 13, while the remainder of the tubes 17a, designated 17ab, are inclined rearwardly and upwardly to define an upper surface of the arch 20 and to rejoin the tubes 17b beyond which point they extend vertically as two parallel rows of spaced tubes to the roof 13. The tubes 17aa and 17ab, like the tubes 17b, extend towards and through the front wall 3, serve to line roof 13, and are connected at their upper ends to the steam and water drum 14. The inlet headers 11 and 18 are connected by suitable downcomers, indicated at 26, to the drum 14.

The side walls 5 and 6 are lined in well known manner with closely spaced steam generating tubes 29 (see Figure 3) connected at their lower and upper ends respectively to inlet and outlet headers (not detailed), and suitably connected by downcomers and uprisers to the steam and water drum 14.

Fuel burners 41 are arranged to discharge pulverized fuel and secondary air into the furnace chamber between the tubes which line the lower part of the front wall 3 below the arch 12.

Arranged adjacent the front wall 3 in the alcove 45 above the arch 12 is a radiant superheater 47 comprising hairpin shaped tubes 48 arranged in groups to form tube platens or panels 49 and with their return bends uppermost and extending through the roof 13 of the furnace chamber, the lower ends of each tube 48 being connected respectively to an inlet header 50 and to an outlet header 51. The inlet header 50 is connected to the steam space of the drum 14 by tubes 52 disposed inside the alcove 45 and positioned on the wall side of the platens 49.

A lateral gas pass 60 extends rearwardly from the gas outlet 19 and communicates at its rearward end with a vertical downpass 61, the rear end portion 62 of pass 60 extending across the full width and across practically half the depth of the downpass 61.

The refractory floor of the part of the lateral gas pass 60 which is rearward of the plane of the furnace rear wall 4 is in the form of a hopper and comprises two parts 65a and 65b respectively on either side of and both downwardly inclined towards a transversely extending opening 66 formed by the upper end of a vertical chute and by-pass 67 disposed at the front side of and extending across the full width of the downpass 61.

The rear end portion 62 of the lateral gas pass 60 and the whole of the downpass 61 are divided by vertical partition walls 72 and 73 (see Figs. 3, 4 and 8) to form three parallel-connected gas flow paths extending respectively from a location above the by-pass 67 to three lateral gas outlets 74a, 74b and 74c arranged at the lower end of the downpass rear wall 75. The downpass is thus divided into three parts 61a, 61b and 61c respectively lying between side wall 77 of downpass 61a and the partition wall 72, between the partition walls 72 and 73, and between the partition wall 73 and side wall 78 of the downpass 61c. Adjustable deflector plates 79a, 79b and 79c are secured to the wall 75 above the level of the opening 66, the plates extending across the widths of the parts 61a, 61b and 61c of the gas pass 61 respectively and each having an inwardly and downwardly sloping upper surface. A partition wall 82 which serves as the front wall of the downpass 61 and as the rear wall of the by-pass 67 is continued downwardly below the outlets 74a, 74b and 74c to the floor 84 of the downpass 61.

The by-pass 67 is connected to an offset downward extension 85 of the downpass 61 by two tunnels 86 extending through the central part 61b of the downpass 61, and the floor 84 is in the form of a plurality of hoppers disposed side by side across the width of the downpass, separate hoppers 90, 91, 92, 93 and 94 being associated respectively with the downpass parts 61a, 61b and 61c and the two tunnels 86, each of these latter two hoppers being extended sidewardly at its front end so that together they include the whole area below the by-pass 67. The lower ends of the by-pass 67 and the downpass 61 constitute gas turning spaces disposed above the hoppers.

The walls and roofs of the lateral gas pass 60 and the downpass 61 include steam heating, wall cooling tubes. Thus an inlet header 100 connected by a suitable conduit indicated at 101 to the outlet header 51 of the radiant superheater 47 is disposed adjacent the lower end of the rear wall 75 of the downpass 61, and has connected to it spaced tubes 103 which extend vertically upwards to line the rear wall 75, at the top of which they are bent forwardly to line the roof 105 of the downpass 61 and the roof 107 of the part of the lateral gas pass 60 rearward of the furnace wall 4, these tubes being bent upwardly adjacent the gas outlet 19 to extend through the roof 107, above which they are connected to a header 108. Other tubes 109 extend horizontally from the inlet header 100 across the downpass 61 to the partition wall 82, and then extend upwardly to a location adjacent the opening 66 to form, with suitable refractory material, the wall 82. At the opening 66, alternate tubes 109a continue vertically upwards through the gas pass 60 as a screen of spaced tubes and through the roof 107 of that pass, above which they are connected to the header 108. The remainder 109b of the tubes 109 are bent rearwardly and inclined upwardly along the part 65b of the floor of the lateral gas pass 60, at the rearmost end of which they are bent upwardly and extend as a screen of spaced tubes upwardly to and through the roof 105 of the downpass 61, above the level of which they are connected to the header 108. Still other tubes, 110, extend horizontally from the inlet header 100

across the downpass 61 and across the by-pass 67 to front wall 111 of the by-pass, and then extend upwardly to line that wall as far as the opening 66, above which alternate tubes 110a are continued upwardly across the lateral gas pass 60 as a row of spaced tubes and through the roof 107, above which they are connected to the header 108. The remainder 110b of the tubes 110 are bent forwardly above the opening 66 to line the part 65a of the floor of the lateral gas pass 60, and adjacent the lateral gas outlet 19 are bent upwardly to extend as a row of spaced tubes across the lateral gas pass 60 and through the roof 107, above which they are connected to the header 108. Parts of the tubes 109a and 110a above the opening 66 are covered with refractory material to define an upward extension 67a of the by-pass 67 while leaving openings 115a, 115b between tubes 109a and 110a respectively for the downward passage into the by-pass of fouling falling on the parts 65b, 65a respectively of the floor of the lateral gas pass 60.

The upper parts of the side walls 77 and 78, the partition walls 72 and 73 and side walls 116a, 116b of the by-pass 67 are also provided with vapor heating tubes. Thus headers 117, 118, 119 and 120 (see Fig. 8) are disposed in the walls 77, 72, 73 and 78 respectively a short distance above the level of the gas outlets 74a, 74b and 74c, and tubes 121, 122, 123 and 124 extend upwardly from the headers 117, 118, 119 and 120 respectively, tubes 121 and 124 serving to line the walls 77, 116a, and 78, 116b respectively, and the tubes 122, 123, together with refractory material, constituting the walls 72 and 73. The tubes 121 and 124 which are associated with the forward ends of the walls 77 and 78 and with the walls 116a, 116b are more closely spaced than the tubes associated with the rearward ends of the walls 77 and 78 (see Fig. 4); and above the level of the opening 66, the more closely spaced tubes 121 and 124 diverge from one another in order that they may line not only the side walls of the gas pass 61 and the upward extension 67a of the by-pass, but also the whole of the side walls of the part of the lateral gas pass 60 rearward of the plane of furnace wall 4. At their upper ends, the groups of tubes 121, 122, 123 and 124 are connected to headers corresponding to the headers 117, 118, 119 and 120, such as, for example, headers 125 and 126 corresponding to headers 118 and 119 respectively. These four upper headers are connected by tubes such as 127 to the header 108.

A convection primary superheater 135 is disposed in the part 61c of the downpass 61 and comprises sinuous tubes 136 arranged in three banks 137a, 137b and 137c in the part of the downpass below the level of the opening 66, the lower end of each tube 136 being connected to an inlet header 138 disposed in the front wall 111 of the by-pass 67 and connected by tubes such as 139 to the headers 117, 118, 119 and 120. Adjacent the level of the opening 66, alternate pairs 136a of the tubes 136 are bent upwardly adjacent the partition wall 82 and are arranged between the tubes 109b to help form the part 65b of the floor of the lateral gas pass 60, at the rearmost end of which they are bent upwardly and extend as two rows of spaced tubes across the rearward end of the gas pass 60 to and through the roof 105, above which they are reversely bent and enter the lateral gas pass 60 to form part of a fourth tube bank 137d of the primary superheater, disposed above the floor part 65b. The remainder 136b of the tubes 136 are bent upwardly at approximately the mid-depth of the downpass 61 to extend upwardly as two rows of spaced tubes to and through the roof 105, where they rejoin the tubes 136a to form the remainder of the tube bank 137d.

In the tube bank 137d, the tubes 136 are arranged at a pitch across the width of the gas pass equal to twice the pitch of the tube parts in the banks 137a, 137b and 137c, and are sinuously bent so that each tube traverses the height of the lateral gas pass several times, and at the forward end of the bank 137d, the tubes 136 extend up-

wardly through the roof 107 and are reversely bent to re-enter the gas pass 60 above the by-pass 67, the tubes being bent to form U-tubes constituting a tube bank 137e of the primary superheater. At the forward end of the tube bank 137e, the tubes 136 extend upwardly through the roof 107 and are connected to an outlet header 149.

A second convection primary superheater 145 is disposed in the part 61a of the downpass 61 and like the superheater 135 comprises sinuous tubes arranged in banks 147a, 147b, 147c, 147d and 147e respectively similar to the banks 137a, 137b, 137c, 137d and 137e.

The outlet header 149 of superheater 135 and the corresponding outlet header of the superheater 145 are both connected by conduits 150 to an attemperator 151, which may be of any suitable known type, and the outlet for cooled steam from the attemperator is connected by conduits 152 to header 153 serving as the inlet header for a secondary convection superheater 155 comprising sinuous tubes 156, each connected at one end to the header 153. The tubes 156 extend downwardly through the roof 107 and are sinuously bent so that each traverses the height of the lateral gas pass several times to form a first tube bank 157a disposed in the part of the lateral gas pass 60 above the arch 20 and between the rows of tubes 17aa and 17ab. At the rearward end of the tube bank 157a, the tubes 156 extend upwardly through the roof 107, and are reversely bent to re-enter the gas pass 60 above the floor part 65a, where the tubes are again sinuously bent to form a second tube bank 157b disposed in the part of the lateral gas path between the rows of tubes 110a and 110b. Both the superheater banks 157a and 157b extend across the full width of the lateral gas pass 60, as indicated clearly in Fig. 3. At the rearward end of the bank 157b, the tubes 156 extend upwardly through the roof 107 and are connected to an outlet header 169, itself connected by a steam main indicated at 161 to the high pressure stage of an associated turbine, not shown.

A convection primary reheat 170 (Fig. 2) is disposed in the part 61b of the downpass 61 and comprises sinuous tubes 171 arranged in three banks 172a, 172b and 172c in the part of the downpass below the level of the opening 66, the lower end of each tube 171 being connected to an inlet header 173 disposed outside the rear wall 75 of the downpass. Adjacent the level of the opening 66, alternate pairs 171a of the tubes 171 are bent upwardly adjacent the partition wall 82 and are arranged between the tubes 189b to help form the part 65b of the floor of the lateral gas pass 60, at the rearmost end of which they are bent upwardly and extend as two rows of spaced tubes across the rearward end of the gas pass 60 to and through the roof 105, above which they are connected to an outlet header 174. The remainder 171b of the tubes 171 are bent upwardly at approximately the mid-depth of the downpass 61 to extend upwardly as two spaced rows of spaced tubes to and through the roof 105, above which they are connected to the outlet header 174.

The outlet header 174 is connected by pipes 175 to the inlet header 180 of a convection secondary reheat 181 comprising tubes 182, the spacing of which transversely of the gas pass 60 is about twice the spacing of the parts of tubes 171 in the tube banks 172a, 172b and 172c transversely of the downpass 61. Each tube 182 is connected at one end to the inlet header 180 and extends downwardly therefrom into the part of the lateral gas pass 60 above the by-pass 67, the tubes being reversely bent at their lower ends so as to form a tube bank 183a. At the rearward end of the bank 183a, the tubes 182 extend upwardly through the roof 107 and are reversely bent to re-enter the gas pass 60 above the floor part 65b, the tubes being reversely bent at their lower ends to form a second tube bank 183b and returning through the roof 107 above which they are connected to an outlet header 185. The inlet header 173 of the primary reheat 170 is connected to the exhaust from a

high pressure stage of the associated turbine, while the outlet header 185 from the series connected secondary reheat 181 is connected to the inlet of an intermediate pressure stage of the associated turbine.

Although in the embodiment of the invention described above, the part 65b of the floor of the gas pass 60 has been described as being composed of tubes 109b, 136a and 171a together with a refractory material 190 (see Fig. 5) which closes the spaces between the tubes, if desired, the refractory material 190 may be omitted, so that the floor part 65b of the lateral gas pass 60 is in the form of a grid formed by the spaced tubes. It is necessary that the tubes constituting the grid be so spaced that they are effective to prevent the downward passage therebetween of any particles of sufficient size to block the spaces between the tubes of the subjacent superheater or reheat banks. In addition, the spacing of these tubes must be sufficiently close to ensure that a sufficient proportion of the hot gases flowing into the downpass shall flow over the superjacent superheater banks 137d and 147d and reheat bank 183b.

The division of the hot gases flowing from the furnace chamber 1 between the parts 61a, 61b and 61c of the downpass 61 and the by-pass 67 is controlled by dampers 200a, 200b and 200c respectively arranged in the gas outlets 74a, 74b and 74c and by dampers 202a and 202b respectively arranged at the rearmost ends of the two tunnels 86.

The offset downward extension 85 of the downpass 61 contains three economizer heat exchange sections 205a, 205b and 205c and is connected at its lower end with a flue 206 leading to a chimney (not shown). The extension 85 is provided with a hopper shaped bottom part 207.

During operation of the unit described, pulverized fuel is supplied to the burners 41 and the hot furnace gases pass upwardly through the furnace chamber and through the lateral gas outlet 19 into the lateral gas pass 60, where they pass over the tube banks of the secondary superheater 155. The division of the hot gases between the parts 61a, 61b and 61c of the downpass 61 and the by-pass 67 will depend upon the settings of the dampers 200a, 200b and 200c, 202a and 202b. The deflector plates 79a, 79b and 79c serve to distribute the hot gases over the depths of the gas pass parts 61a, 61b and 61c respectively. From the downpass 61 the hot gases pass downwardly through the extension 85 and into the flue 206 whence they pass to the associated chimney.

Vapor generated in the tubes lining the walls of the furnace chamber 1 is separated from the entraining water in the steam and water drum 14, whence the steam flows through tubes 52 to the radiant superheat 47. From the superheat 47 the steam flows through conduit 101 to the inlet header 100 and thence through the tubes 103, 109 and 110 to the header 108, through tubes 127 to the upper headers such as 125 and 126 associated with the tubes 121, 122, 123 and 124, downwardly through those tubes to the headers 117, 118, 119 and 120 and thence through the tubes 139 to the inlet headers, for example the header 138, of the primary superheaters 135 and 145. The steam flows through the parallel connected primary superheaters 135 and 145, through the conduits 150 to the attemperator 151, and thence through the conduits 152 to the inlet header 153 of the single secondary superheat 155, and finally passes from the superheat through the steam main 161 to the high pressure stage of the associated turbine.

Steam exhausted from the high or an intermediate pressure stage of the steam turbine is supplied to the inlet header 173 of the primary reheat 170, and passes from the outlet header thereof through the pipes 175 to the inlet header of the secondary convection reheat 181, from the outlet header 185 of which it is returned to an intermediate or low pressure stage of the associated turbine.

During operation, the temperatures of superheat and reheat may be controlled by regulation of the quantity of gases flowing through the by-pass 67 upon adjustment of the dampers 202a, 202b, the temperature of reheat may be controlled by operation of the dampers 200a, 200b and 200c to regulate the distribution of gases between the parallel-connected side parts 61a and 61c of the downpass 61 on the one hand and the central part 61b on the other hand. A rapidly effective control of superheat temperature may also be had by means of the attemperator 151. Suitably, automatic control means are provided to effect adjustment of the dampers and the attemperator in accordance with deviations from predetermined values of the superheat and reheat temperatures.

It is found that in the operation of a unit such as that described, deposits tend to accumulate on the tubular heat exchanger surfaces. Such accumulations are periodically dislodged by operation of fluid heater cleaners arranged for the discharge of cleaning fluid over the tubular surfaces, and by virtue of the particular gas pass arrangement described and illustrated, when the part 65b of the floor of the gas pass 60 is imperforate, as illustrated in Fig. 5, accumulations dislodged from tubes in the lateral gas pass 60 do not fall onto the tube banks disposed in the downpass 61, but are diverted into the chute or by-pass 67 and fall into the hoppers 93 and 94, from which they may be removed as and when desired. Suitable fluid heater cleaners or soot blowers are operable at distributed positions such as 210—229 (Fig. 1). Such a soot blower is indicated by the Snow et al. Patent 2,110,534, Mar. 8, 1948, or Patent 2,126,683.

In the alternative arrangement referred to above, in which the refractory material is omitted from the floor part 65b of the pass 60, the larger pieces of dislodged accumulations are caused to fall downwardly through the chute or by-pass 67, and only the smaller pieces, which can fall between the tubes in the downpass 61, are allowed to fall through the floor into the downpass 61. By the correct spacing of the tubes which form the grid, only pieces of such size as will pass between the tubes in the tube banks in the gas pass 61 are permitted to enter the downpass.

Dislodged deposits falling downwardly through the gas downpass parts 61a, 61b and 61c are collected in the hoppers 90, 91 and 92 respectively, from which they may be removed as and when desired.

Deposits dislodged from tube banks in the parts of the gas pass 60 above the floor part 65a and above the by-pass 67 also fall downwardly through the by-pass 67 and are collected in the hoppers 93 and 94. Deposits dislodged from the part of the lateral gas pass above the arch 20 will fall into the furnace chamber.

Referring now to Figs. 9 and 10, these illustrate a modification of the construction illustrated in Figs. 1 to 8, according to which the lateral gas pass extends above the downpass from one side thereof as far as the opposite side thereof. In most respects it is similar to the embodiment so far described, and similar parts are denoted by the numerals used in the first embodiment. However, a gas turning space 300 is provided by a protuberance 301 built onto the upper end of the rear wall 75 of the gas pass 61, the space 300 being divided into three parts by rearward extensions of the walls 72 and 73. The lower end 302 of the protuberance 301 is formed as three hoppers for the collection of ash separated from the furnace gases as they pass through the three parts of the space 300 respectively.

In this arrangement, the tube banks 147d, 147e, 137d, 137e, 183a and 183b are all disposed above the part 65b of the floor of the lateral gas pass 60; the upper ends of the tubes 109b are continued a short distance beyond the tubes 103 which line the downpass rear wall 75 and then extend as a row of spaced tubes to and through the roof 107; and the tube parts 136a, 136b, 171a and 171b are

continued towards and extend upwardly adjacent the rear wall 303 of the gas turning space 300.

In this embodiment, the part 65b of the floor of the lateral gas pass 60 may include refractory material as shown in Fig. 5, or the refractory material may be omitted and the floor left as a grid of suitably spaced tubes.

The operation of the embodiment shown in Figs. 9 and 10, and of that embodiment with the modification wherein the floor 65b is in the form of a tubular grid, is as described above with reference to Figs. 1 to 8.

In the arrangements described, furnace gases may safely be admitted to the lateral pass at high temperature and adequate heat exchange surface is provided for suitably cooling the gases before they reach the downpass. The high temperature of the gases at the inlet to the superheater, the transverse flow of the gases over all the vapor heating tubes and the extension of the lateral pass over the downpass enable a relatively compact arrangement to be achieved. The vapor heating surface arrangement described, utilizing wide tube spacing and upright pendent tubes in the pass 60, enables adequate cleaning means to be installed and to be effectively used and suitable provision is made for the disposal of matter dislodged from the vapor heating tubes in the gas pass 60.

Although the invention has been described with reference to the details of preferred embodiments, it is to be understood that the invention is not to be considered as limited to all of the details thereof. It is rather to be taken as of a scope commensurate with the scope of the subjoined claims.

What is claimed is:

1. In a vapor generating and superheating unit, a furnace having its walls lined with vapor generating tubes, means firing the furnace with a fuel resulting in solid particles in suspension in the furnace gases, means forming a gas pass leading from the furnace, a secondary vapor superheater in an upper part of the gas pass, a primary superheater in a lower part of the gas pass and at least partly disposed beneath the secondary superheater, means periodically dislodging solids accumulations on the secondary superheater, means forming a disposal zone for dislodged solids beyond the primary superheater relative to gas flow, means forming a primary superheater gas by-pass leading from a position beneath the secondary superheater to said disposal zone whereby accumulations dislodged from the secondary superheater pass to the disposal zone without contacting the primary superheater, and gas flow regulating means for controlling the amount of gas flow through the by-pass.
2. In a vapor generating and superheating unit, a furnace having its walls lined with vapor generating tubes, means firing the furnace with a fuel resulting in solid particles in suspension in the furnace gases, means forming a gas pass leading from the furnace, a secondary vapor superheater in an upper part of the gas pass, a re heater in a lower part of the gas pass and at least partly disposed beneath the secondary superheater, means periodically dislodging solids accumulations on the secondary superheater, means forming a disposal zone for dislodged solids beyond the re heater relative to gas flow, means forming a re heater gas by-pass leading from a position beneath the secondary superheater to said disposal zone whereby accumulations dislodged from the secondary superheater pass to the disposal zone without contacting the re heater, and gas flow regulating means for controlling the amount of gas flow through the by-pass.
3. In a vapor generating and superheating unit, a furnace having its walls lined with vapor generating tubes, means firing the furnace with a fuel resulting in solid particles in suspension in the furnace gases, means forming a gas pass leading from the furnace, a secondary vapor superheater in an upper part of the gas pass, a

primary superheater having a part disposed in a lower part of the gas pass and at least partly disposed beneath the secondary superheater, means periodically dislodging solids accumulations on the secondary superheater, means forming a disposal zone for dislodged solids beyond the primary superheater relative to gas flow, means forming a primary superheater gas by-pass leading from a position beneath the secondary superheater to said disposal zone whereby accumulations dislodged from the secondary superheater pass through the by-pass to the disposal zone without contacting the primary superheater, and gas flow regulating means for controlling the amount of gas flow through the by-pass, the by-pass having downwardly converging hopper-like walls at its entrance immediately below the secondary superheater.

4. In a vapor generating and superheating unit, a vertically elongated furnace, means firing the furnace with a fuel resulting in solid particles in suspension in the furnace gases, vapor generating tubes lining the walls of the furnace, a lateral gas pass leading rearwardly from the upper part of the furnace, upright tubes forming a pendent secondary superheater disposed in the inlet section of said gas pass, other upright tubes forming the pendent section of a primary superheater subject to gas flow in said pass next after the secondary superheater, an inlet header for the primary superheater, means forming a downflow gas pass leading from the outlet of the lateral gas pass, upright partition walls including superheater wall tubes dividing the downflow pass into a middle reheat pass and two symmetrical side passes, a reheat in the middle pass, primary superheater components in said side passes, means including superheater wall tubes forming a gas by-pass for the reheat and primary superheater components, the by-pass leading downwardly from the lateral gas pass at a position forwardly of the downflow pass and having a hopper-like inlet for receiving deposits dislodged from the secondary superheater, means for dislodging deposits from the secondary superheater, hoppers constituting solids disposal zones at the lower ends of the by-pass as well as the middle reheat pass and the superheater side passes, means for independently controlling gas flow through the by-pass as well as the reheat pass and the side passes, means including said superheater wall tubes for conducting superheated steam from the vapor generating tubes to the inlet header for the pendent primary superheater section, steam flow connections whereby steam flows from the pendent primary superheater section to the superheater components in said side passes and then through said components to the secondary superheater, the reheat including a pendent section of upright tubes receiving reheated steam from the reheat in said middle pass, and means including an attemperator whereby superheated steam is conducted to the secondary superheater.

5. In a vapor generating and superheating unit, a vertically elongated furnace, means firing the furnace with a fuel resulting in solid particles in suspension in the furnace gases, vapor generating tubes lining the walls of the furnace, a lateral gas pass leading rearwardly from the upper part of the furnace, an inwardly extending furnace wall arch disposed below the inlet to said gas pass, a similar arch extending from the front furnace wall into the furnace at a level below that of the first arch and forming an alcove with the furnace surfaces thereabove, upright tubes forming a radiant superheater disposed in said alcove, upright tubes forming a pendent secondary superheater disposed in the inlet section of said gas pass, other upright tubes forming the pendent section of a primary superheater subject to gas flow in said pass next after the secondary superheater, means forming a downflow gas pass leading from the outlet of the lateral gas pass, upright partition walls including superheater wall

tubes dividing the downflow pass into a middle reheat pass and two symmetrical side passes, a reheat in the middle pass, primary superheater components in said side passes, means including superheater wall tubes forming a gas by-pass for the reheat and primary superheater components, the by-pass leading downwardly from the lateral gas pass at a position forwardly of the downflow pass and having a hopper-like inlet for receiving deposits dislodged from the secondary superheater, means for dislodging deposits from the secondary superheater, hoppers constituting solids disposal zones at the lower ends of the by-pass as well as the middle reheat pass and the superheater side passes, means for independently controlling gas flow through the by-pass as well as through the reheat pass and the side passes, means conducting generated vapor from the furnace wall tubes to the radiant superheater, means including said superheater wall tubes for conducting superheated steam from the radiant superheater to the inlet header for the pendent primary superheater section, steam flow connections whereby steam flows from the pendent primary superheater section to the superheater components in said side passes and then through said components to the secondary superheater, the reheat including a pendent section of upright tubes receiving reheated steam from the reheat in said middle pass, and means including an attemperator whereby superheated steam is conducted to the secondary superheater.

6. In a vapor generating and superheating unit, a vertically elongated furnace, means firing the furnace with a fuel resulting in solid particles in suspension in the furnace gases, vapor generating tubes lining the walls of the furnace, a lateral gas pass leading rearwardly from the upper part of the furnace, upright tubes forming a pendent secondary superheater disposed in the inlet section of said gas pass, other upright tubes forming the pendent section of a primary superheater subject to gas flow in said pass next after the secondary superheater, an inlet header for the primary superheater means forming a downflow gas pass leading from the outlet of the lateral gas pass, upright partition walls including superheater wall tubes dividing the downflow pass into a middle reheat pass and two symmetrical side passes, a reheat in the middle pass, primary superheater components in said side passes, means including superheater wall tubes forming a gas by-pass for the reheat and primary superheater components, the by-pass leading downwardly from the lateral gas pass at a position forwardly of the downflow pass and having a hopper-like inlet for receiving deposits dislodged from the secondary superheater, means for dislodging deposits from the secondary superheater, hoppers constituting solids disposal zones at the lower ends of the by-pass as well as the middle reheat pass and the superheater side passes, means for independently controlling gas flow through the by-pass as well as through the reheat pass and the side passes, means including said superheater wall tubes for conducting superheated steam from the furnace wall tubes to the inlet header for the pendent primary superheater section, steam flow connections whereby steam flows from the pendent primary superheater section to the superheater components in said side passes and then through said components to the secondary superheater, the reheat including a pendent section of upright tubes receiving reheated steam from the reheat in said middle pass, and means including an attemperator whereby superheated steam is conducted to the secondary superheater, one wall of said hopper-like inlet being disposed above the primary superheater components and including tubes spaced apart to permit only small particles of dislodged accumulations to pass therebetween and thence to said components.
